UNITED STATES PATENT OFFICE

149,406

DESIGN FOR A COMBINED RADIO, CLOCK,
AND LAMP

Irving Engel, East Orange, N. J., assignor to
Crystallite Company, East Orange, N. J., a cor-
poration of New Jersey

Application November 7, 1946, Serial No. 134,570

Term of patent 3½ years

(Cl. D56—4)

To all whom it may concern:

Be it known that I, Irving Engel, a citizen of the United States, residing at East Orange, in the county of Essex and State of New Jersey, have invented a new, original, and ornamental Design for a Combined Radio, Clock and Lamp, of which the following is a specification, reference being had to the accompanying drawing, forming part thereof.

Figure 1 is a perspective view of a combined radio, clock and lamp, showing my new design.

Figure 2 is a front elevation of the same.

The appearance of the rear portion of the combined radio, clock and lamp, not shown, is substantially similar to that of the front portion illustrated, with exception that the clock and radio

dials, hands and control knobs are omitted at the rear.

I claim:

The ornamental design for a combined radio, clock and lamp, as shown and described.

IRVING ENGEL.
